CLAIM

The ornamental design for a childproof storage container, as shown and described.

DESCRIPTION

FIG. 1 is a perspective front view of a first embodiment of a childproof storage container according to the present invention;

FIG. 2 is a perspective back view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a perspective front view of a second embodiment of the childproof storage container according to the present invention;

FIG. 10 is a perspective back view thereof;

FIG. 11 is a front view thereof;

FIG. 12 is a rear view thereof;

FIG. 13 is a right side view thereof;

FIG. 14 is a left side view thereof;

FIG. 15 is a top view thereof; and,

FIG. 16 is a bottom view thereof.

The broken lines illustrate portions of the childproof storage container and form no part of the claimed design.
